COMBINED LOCKET AND DOLL

David Weissmann, Palos Verdes Estates, Calif., assignor to Mattel, Inc., a corporation of California

Filed Mar. 1, 1967, Ser. No. 6,022

Term of patent 14 years

(Cl. D45—15)

FIG. 1

I claim:

The ornamental design for a combined locket and doll, as shown and described.
